UNITED STATES PATENT OFFICE

EDWIN ANDERSON, OF LOS ANGELES, CALIFORNIA

VENETIAN BLIND BRACKET

Application filed July 26, 1930. Serial No. 470,973.

The present invention relates to brackets and actuators for Venetian or Louvre blinds. The object of the present invention is the provision of a very simple and economical 5 Venetian blind bracket and actuator, which is very rugged and durable, and which is of such construction as to be compact and inconspicuous and which also enables the blind to be readily removed from the supporting brackets and replaced without disturbing the actuating parts, thus rendering the dusting, cleaning or removing and replacement of the blind a very simple and easy operation which can be performed by 10 anyone without difficulty.

The invention resides in the sundry novel details of construction, combination and arrangement of parts of the brackets and actuator, which will appear as the specification 20 proceeds, and which will be particularly pointed out in the subjected claims.

In the drawings, which show the preferred embodiment of the invention as devised:

Figure 1 is a front elevation of a Venetian blind supported in a window opening by the brackets and actuator of the present invention;

Figure 2 is a vertical sectional view taken substantially on line 2—2 of Figure 1;

Figure 3 is a fragmentary transverse sectional view taken substantially on line 3—3 of Figure 2;

Figure 4 is a fragmentary sectional view taken substantially on line 4—4 of Figure 2;

Figure 5 is a view showing two detachable and interengaging parts of the bracket-actuator, in disassembled relation for supporting one end of the blind; and

Figure 6 is a perspective view of a supporting bracket used at the other end of the blind.

The Louvre or Venetian blind shown in Figures 1 and 2 consists of a plurality of spaced superposed slats 10 supported or connected together by such means and in such a manner as to be brought into overlapping or edge to edge position, or to be shifted to lie in spaced parallel position. This is usually accomplished by two pairs of straps, cables or chains 11, one pair being positioned at each end portion of the blind and having the slats

positioned between said cables or straps and secured thereto. The cables or straps 11 are connected to a top or header slat 12 so that by tilting the header slat 12 from vertical to horizontal position or intermediate positions, the desired adjustment of the slats 10 can be obtained. These blinds are usually provided with raising and lowering means whereby the slats 10 may be moved adjacent the header slat to raise the blind or drop it, as indicated in the drawings, to lower the blind. However, such raising and lowering means are not shown in this disclosure. Blinds of this type are well-known in the art, and the present invention is applicable to any blind of this general type.

The invention resides particularly in the combined bracket-actuator indicated by the character A. This bracket-actuator A comprises a bracket proper 14, which consists of a depending plate having a laterally extending flange 15 at its upper edge. The depending plate of the bracket is reduced in width toward its lower end and is formed with a laterally extending boss 16 on the inner face of its lower extremity from which rises a substantially vertical rib 17. An opening 18 is provided through the boss and the plate through which a rivet or spindle 19 extends for securing in position a segmental gear 20. In the present instance, the member 19 is in the form of a hollow ended rivet which extends through an opening in the segmental gear, the hollow end being spread in the opening to firmly bind the segment to the rivet, the rivet rotating in the opening 18.

The segmental gear 20 is actuated by a worm 21 carried on the shaft 22 which is supported in bearing lugs 23 and 23' formed on the inner face of the plate near one corner thereof. These lugs are in the form of lateral projections having aligned openings therein through which the shaft 22 extends. The gear and worm are positioned so that they mesh throughout the perimeter of the gear. The other end of the shaft 22 has fastened thereon a pulley wheel 24, having a tapering groove 25 therein extending around its periphery in a circuitous or serpentine fashion for receiving a pulley cord 13. The lug 23 is

formed with a disc 26 having a laterally extending flange 27 extending from the upper portion of its edge to overlie the periphery of the pulley 24, and to partially house the 5 pulley. Thus it will be seen that because of the tapered serpentine character of the groove 25 and the position of the shield flange 27, the pulley cord will frictionally bind in the groove and against the under face of the 10 flange 27 so as to hold the pulley in any adjusted position. However, the pulley can be readily rotated in either direction on its axis by a deliberate pull upon the cord sufficient to overcome the said frictional resistance. Of 15 course, it will be understood that the gear 20 and the worm 21 provide a substantial locking means to prevent actuation of gear under the strains or stresses which may be applied to the gear through the blind.

20 The bracket-actuator just described consists of a minimum of parts. The parts 14, 15, 16, 17, 23, 23', 26 and 27 are preferably one casting. The worm 21 and the shaft 22 are preferably one casting having the pulley 25 wheel 26 riveted thereon. This bracket-actuator is secured at the top of a window or door opening to the under surface thereof by suitable fasteners, such as screws, nails, or the like, extended through openings in the 30 flange 15 so as to suspend the bracket-actuator in a manner well understood in the art, and as clearly shown in Figures 1 and 2 of the drawings, for supporting one end of the 35 Venetian blind header slat 12, the other end of the header slat being rotatably supported in a slotted bearing bracket B.

In order to support the header slat on the bracket-actuator A, the segmental gear 20 is provided with an extension or shiftable member 20' having, preferably, a pair of openings 28 therein, one arranged on each side of 40 its axis or pivot pin 19. These openings 28 are for the purpose of receiving two projecting pins 29 carried on a coupling member 30. This coupling member preferably consists of an angular strip of rigid material adapted to be fixedly secured to one end of the header slat, as clearly shown in Figures 3 and 4.

50 Of course it is within the perview of the present invention to substitute for the two openings and their complemental connecting pins 29, a single angular opening and a corresponding pin. However, by the present arrangement, the pins 29 are made sufficiently long to project through the openings 28 and strike with the rib 17, which thus performs, not only the function of a staying support for the segmental gear 20, but serves to limit 55 the rotative movements of the gear in both directions of its movement. By so limiting the movement of the gear 20, the latter is prevented from disengaging with the worm so long as the pins 29 are in the openings 60 65 28.

The bracket B consists of an angular member having one leg *x* formed with openings through which fastening members may pass for securing the bracket in position to the under side of the top of a window opening, or the like; the other leg depending and formed with an angular slot *y* extending from one of its side edges for a distance inwardly and then downwardly, the last mentioned portion of said slot having a restricted portion therein which tends to hold a trunnion 31 on one end of the header slot 12 from accidental displacement.

It will thus be manifest that a Venetian blind can be readily removed from its supporting brackets A and B by lifting the trunnion 31 from the slot *y* of the bracket B which will permit the coupling pins 29 to be withdrawn from the openings 28 on the segmental gear 20 without disassembling any of the actuating parts of the actuator. It is obvious also that the blind may be positioned in place by first inserting the pins 29, on one end of the header slot 12, into the openings 28, and then inserting the trunnion 31 in the slot *y* of the bracket B.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

What is claimed as new is:

1. A supporting bracket for Venetian blinds comprising a bracket, a shiftable member mounted on the bracket for tilting the header of the blind, means for actuating said shiftable member, attaching means carried by the header of the blind and removably interengageable with said shiftable member.

2. A supporting bracket for Venetian blinds comprising a bracket, a member rotatably mounted on said bracket, and an attaching member securable to the header of said blind and having projecting means thereon removably interengaging said rotatable member to move therewith and to support said header, and means for actuating said rotatable member.

3. A supporting bracket for Venetian blinds comprising a bracket, a rocker member mounted on said bracket and supported thereby, and projecting means carried on the header of said blind and removably insertable in a complemental opening in said rocker member whereby the header is supported by and moves with said member, and means for actuating said rocker member.

4. A bracket for Venetian blinds comprising a bracket plate, a rotatable member mounted on said plate, and an attaching

member securable to the header of said blind and having a pair of spaced projections removably insertable in openings in said rotatable member and means for actuating said

5 rotatable member.

5. A supporting bracket for Venetian blinds comprising a bracket plate having means whereby it may be secured in position, a segmental gear pivotally mounted on said 10 plate, a worm mounted on said plate and meshing with said segmental gear, a pair of spaced projecting pins carried by the head of the blind and removably insertable in openings in said segmental gear.

15 6. A supporting bracket for Venetian blinds comprising a bracket plate having means whereby it may be secured in position, a segmental gear rotatably mounted on said 20 plate, a worm mounted on said plate and meshing with said segmental gear, a rib on said plate and lying between said segmental gear and said plate, and an attaching bracket 25 securable to the header of said blind and having a pair of spaced projecting pins there- on removably insertable in openings in said 30 segmental gear and adapted to alternately engage said rib.

7. A supporting bracket for Venetian blinds comprising a bracket member having 35 means whereby it may be secured in position, a rotatably movable member for attachment to the blind header, means for actuating said movable member, including a grooved pulley, a flexible pulley element trained over the 40 grooved pulley, and a projection on said bracket extending partially around the periphery of the pulley and opposite said groove therein.

8. The combination with a Venetian 45 blind having a header, of supporting bracket means comprising a bracket for one end of the header including a bracket member, a rotatably shiftable member on said bracket member, means whereby said member may be 50 actuated, means on the end of said header removably insertable in said shiftable member; and a bracket for the other end of said header comprising a slotted bracket member, and a trunnion on said other end of the header 55 readily insertable into and removable from said slotted bracket member.

9. A supporting bracket for Venetian blinds comprising a bracket member having an abutment thereon, a rotatable member 60 mounted on said bracket, means for actuating said rotatable member, said bracket including attaching means carried by the header and removably attachable to said rotatable member, whereby the header may be tilted 65 by the movement of said rotatable member, said attaching means also being positioned to cooperate with the abutment, when in attaching position for limiting the movement of said rotatable member.

65 10. A supporting bracket for Venetian

blinds comprising a supporting member, operable means mounted on said bracket member for tilting the header of Venetian blinds, said bracket including attaching means carried by the header and removably inter- 70 gageable with said operable means whereby the header may be supported in position and readily removable therefrom.

11. The combination with a Venetian blind having a header, of blind supporting means 75 comprising a bracket member for one end of the header, operable means on said bracket member for tilting said header, and means carried by the header removably inter- 80 gageable with an operative element of said operable means whereby said end of the blind is supported, and a bracket member for the other end of the header comprising a slotted bracket member, and a trunnion on said other 85 end of the header readily movable into and removable from the slot of said last bracket member.

12. A supporting bracket for Venetian blinds including a bracket member having 90 means whereby it may be secured in position, a gear element rotatably mounted on the bracket, a worm rotatably mounted on the bracket and meshing with said gear element, a shiftable member rotatable by said gear element and having a pair of spaced openings 95 therein, and a pair of spaced projecting pins carried by the header of the blind and removably insertable in said openings in said member.

13. A supporting bracket for the Ve- 100 netian blinds including a bracket having means whereby it may be secured in position, a gear element rotatably mounted on the bracket, a worm rotatably mounted on the bracket and meshing with said gear element, 105 a shiftable member rotatable by said gear element and having a pair of spaced openings therein, one on each side of the axis of rotation of said member, and an attaching means including a pair of spaced projecting pins carried by the header of the blind and removably insertable in said openings in said 110 shiftable member to project beyond said openings, and an abutment on the bracket to be alternately engaged by extremities of said pins during the rotative movements of said shiftable member to limit the movements thereof.

In testimony whereof I have hereunto set 115 my hand.

EDWIN ANDERSON.
